TYPEWRITING MACHINE

William F. Helmond, West Hartford, Conn., assignor to Underwood Elliott Fisher Company, New York, N. Y., a corporation of Delaware

Application December 2, 1933, Serial No. 700,646

18 Claims. (Cl. 197—25)

This invention relates to improvements pertaining to the general construction and designing of standard noiseless typewriters, of which examples are seen in patents to Going, No. 5 1,604,640, of October 26, 1926, and No. 1,682,330, of August 28, 1928. In said noiseless typewriters, the typed line is exposed to view, by the usual ribbon-vibrator (not shown).

In said patents, the noiseless types print upon 10 the very front of the platen upon a line which is level with the platen-axis. After each type-impression, the vibrator drops the ribbon. The type-slides are grouped radially in front of the platen and work in guides which rise above the 15 top of the platen. The front portions of the type-bars are covered by a segmental shell which rises still farther than the type-bar-guiding segment. In consequence, the line of typing upon the platen is more or less hidden from view, thus 20 substantially reducing one of the chief benefits formerly derived in front-strike hammer-blown machines, in which the work was always in plain view, after it had been exposed by the dropping of the ribbon-vibrator.

25 In said Going patents, the designing of the framework and mechanism is such that the parts follow the usual designing principle of occupying horizontal and vertical positions in most cases, the body of the type-bar reaching as high as the 30 top of the platen and the type-bar-operating parts dropping nearly to the level of the key-levers.

An object of this invention is to make a substantial improvement in the visibility of the typed 35 line, and to effect this improvement at a minimum of expense, and also to improve the appearance and saleability of the machine.

To accomplish this and other results, a change 40 is effected in the setting of the mechanism which is confined within the casing of the machine, and some changes are made in the casing also. The internal mechanism is swung downwardly 45 as a unit at the front portion of the machine. The position of this general unit is determined by swinging it bodily down around the axis of 50 the platen, whereby the platen retains its former position, but the upper front portion of the unit is dropped about an inch and a half. Thus, by this means, the type-bars when in normal positions are made to occupy much lower positions than formerly, and the same is true of the segments and other parts just in front of the platen, and which guide the type-bars, and also of the front shell which overlies the type-bars. The 55 internal mechanism-unit as shown at Figure 2 of

the accompanying drawings is in this manner inclined downwardly about ten degrees from its former level position according to the former normal designing of the machine.

This abnormal inclination of the machine does not extend to the casing, since the side, front and rear walls of said casing may retain their former vertical positions; also the base and the front portion of the open frame which encloses the keyboard may retain their horizontal and erect features. The types no longer strike upon a line which is level with the platen-axis, but upon a line which is found by intersecting the platen by a plane which, while passing through the platen-axis, is inclined ten degrees from the 10 platen-axis level. The line of printing, although a trifle under the level of the platen-axis, is clearly visible because of the relatively greater drop of the parts forward of the platen where are 15 found the bulky segmental guides and the top shell. These are lowered so much that the typewriting is readily visible, whereby great advantage is gained.

The improvement is so designed that not only 25 vertical and horizontal lineaments are preserved in the general frame-work, but also in the keys themselves; the keys occupying the same positions at the front of the machine that are occupied in former machines, as exemplified in said Going patents. The key-levers extend rearwardly 30 from said keys, and the machine generally presents the same appearance to the purchaser as former machines, except that a substantial reduction is effected in the height of the machine just at the rear of the keyboard.

The deep portions of said inclined general unit 35 include the bodies of the key-levers, whereas the key-bearing portions of the key-levers at the front are not dropped or inclined. There is therefore a fault or break in the key-lever system 40 analogous to the faults which are often found in strata of the earth. The break in the key-lever system is brought about by inclining the rear portions of the levers which were formerly level, and maintaining the former level of the front 45 portions of the levers and having the front portions joining the rear portions at the break.

Although the general mechanism of the machine is thus inclined, its operation remains of the same high quality as heretofore.

The inclined unit takes in not only the type-bars and the rear portions of the key-levers, but also the carriage-escape mechanism, many of the carriage-devices, and part of the tabulating mechanism.

The paper-carriage is constructed on level lines from back to front, and the entire exterior of the machine has an erect, level appearance, so that no objection rises from the downward and forward inclination of the general mechanism-unit which is enclosed in the casing.

The aforesaid lowered or declined segmental shell or top cover which overlies the type-bar system may agree in its declination with that of the general interior unit; the declination of the top segmental cover softens the contour of the upper part of the machine, and therefore improves the appearance of the machine, while visibility of the typing line is greatly improved.

Another feature of invention relates to tabulating mechanism. There is shown a series of key-settable tabulating stops mounted in a rack carried by the carriage. A series of key-operated denominational stops, co-operative with the key-set stops on the carriage, are housed in a compact column-like frame, to form a readily attachable unit supported by, and at the rear of, the typewriter-framework, said stop-housing frame preferably extending vertically, in consonance with the desired erect lines of the machine-contour. The denominational stops are in the form of vertical blades whose lower ends are detachably connected to denominational key-levers operable to lift said blades. Heretofore, in order that such blades could, by lifting thereof, be made to co-operate with the carriage-carried stops, the latter were disposed above the tops of the blades.

The present improvements include novel blade-guiding means whereby the denominational-stop blades when they are lifted are at the same time moved forwardly for the purpose of projecting them toward the carriage-carried stops which are disposed forwardly of the upper front edges of the blades, and are therefore co-operative with the latter both in upper-case and lower-case positions of the carriage. The denomination-stop blades have the usual close letter-spacing.

The novel blade-guiding means include an abutment for upwardly-facing edges presented preferably by the extreme upper ends of the denominational-stop blades, said abutment and edges being arranged at such inclination that when a blade is lifted by the key-lever, the upper end portion of the blade is at the same time forced forwardly into the path of the set stops on the carriage. The blade-guiding surface of the abutment may be formed by the bottoms of spaced slots in said abutment, said slots effecting the aforesaid close spacing of the blades, and the sides of the slots supporting the blades against the lateral thrust which they receive when arresting the carriage. Thus said slotted abutment acts as a spacing means for the blades, and as a means to force the blades forwardly when they are lifted, and also as a means for supporting the blades against said lateral thrust. A guide, which may be also slotted, is spaced below said blade-end-guiding abutment, and keeps the blades articulated with the latter when they are retracted, said lower guide co-operating to force the blades rearwardly when they are retracted.

The aforesaid housing which mounts the denominational-stop blades also mounts a cross-shaft to which is fastened a universal bar operable, by the lifting of any one of the blades, for effecting release of the carriage from the escapement devices. Slidable along the cross-shaft, and also rockable thereabout, is a sleeve

or yoke having an arm forming a stop-setting finger and another arm directly articulated to another blade which is mounted alongside the denominational-stop blades, so that it may be connected at its lower end to a stop-restoring key-lever in the same manner as the denominational blades are connected to key-levers. The yoke, rockable about said cross-shaft, the additional blade articulated therewith, and the corresponding key-lever form a stop-setting train. The stop-setting finger of the yoke is opposite the front of the fore-and-aft shiftable key-settable stops on the carriage, and the mounting of the yoke on the cross-shaft of the universal bar conduces to compactness of assembly. Lengthwise of the universal-bar shaft, the stop-setting yoke is held in normal position by a spring, to the end that should the carriage be released while the stop-setting finger of the yoke is between adjacent stops on the carriage, the yoke and its finger will move along with the carriage to avoid jamming the finger and obstructing its spring-pressed retraction.

Similar to the aforesaid denominational blades is an additional blade liftable by a key-lever and acting as a stop-restorer, said stop-restorer blade being guided at its upper end by the same abutment and lower guide which guide the denominational blades. Thus the stop-restoring key-lever projects the stop-restoring blade forwardly at the same time that the latter is lifted, the forward projecting of the stop-restoring blade serving to restore a key-set stop on the carriage that has been tabulated to the denominational blade of lowest denomination. The stop-restoring blade may also have a cam operative when the blade is held in its operative position by its key to restore all the stops on the carriage by a run of the latter.

Still another feature of invention relates to improved means for adjusting the platen toward or from the normal printing-plane of the types, in accordance with the number of work-sheets being typed upon. The improved platen-adjusting means include a front and center part of a fore-and-aft shiftable platen-carriage support, said part forming an adjustable abutment which follows a cam mounted on a shaft reaching to the outer side of the machine, where said shaft presents a handle by which it may be manipulated. Springs force the carriage so that said cam-following abutment always bears against the cam, whereby the position of the carriage-support and hence of the platen depends on the angular position of said cam-shaft as determined by said handle and a co-operative detent.

The guiding of the front part of said carriage-support may be effected in a known manner. At the rear portion of the slidable support, improved means are employed for slidably guiding said rear portion, to the end that requisite alignment of the rear of the slidable support and rear guiding means may be facilitated and the parts constituting such rear guiding means simplified.

Other features and advantages will hereinafter appear.

In the accompanying drawings, Figure 1 is a fragmentary side elevation view, showing details of the improvements for guiding the carriage-support at its rear for fore-and-aft adjustment.

Figure 2 is a cross-sectional side elevational view of a noiseless typewriter, the section being taken through the middle of the machine, and showing how the internal mechanism-unit

the machine-frame has been turned about the platen-axis to improve visibility of the printing-line.

Figure 3 is a top plan view, showing details of the improved means for guiding the platen-carriage support at its rear portion for fore-and-aft adjustment in accordance with the number of work-sheets on the platen. The view also shows details of the improved means manually operable for making the carriage-support adjustment.

Figure 4 is a fragmentary side view, showing arrangement of a handle and detent whereby the carriage-support adjustment is manipulated and gaged.

Figure 5 is a side elevation view of the typewriter, showing how the erect lines of the typewriter frame or casing and of the keyboard are preserved, said view also showing how the depression of a front top cover-shell of said machine-casing softens the contour of the latter.

Figure 6 is a perspective view of the improved tabulating-stop mechanism.

Figure 7 is a top plan view, indicating how the tabulating mechanism seen in Figure 6 is modified to act as a one-key column-tabulator, Figure 7 also showing the relative arrangement of a stop-setting key-lever, a stop clearing or restoring key-lever, and a novel column-tabulating key-bar.

Figure 8 is a top plan view of some of the key-settable stops on the carriage and the relation to the latter of the stop-setting finger, the counter-stop blade, and the stop-restoring blade.

As seen in Figure 2, the typewriting instrumentalities at the rear of the keyboard are mounted within a casing or machine-frame 15, and are substantially along the lines shown in said Going Patent 1,682,330 in respect to the functions of the individual parts of said instrumentalities. Said instrumentalities include type-actions 16, each mounted upon an individual bracket 17 supported on a segment 18. Each type-action 16 operates a type-carrier 20, the type-actions being operable as set forth in said Going patent, so that, upon operation of either one of a pair of alphabet or numeral keys 21 of a keyboard 22, a type-carrier common to said pair of keys is projected rearwardly from the normal position, seen in Figure 2, to print noiselessly by pressure against platen 24. Depending on which one of said pair of keys is operated, the type-carrier 20 is so guided, in its headlong movement, by the type-action that either an upper type 26 or a lower type 27 of the carrier is brought into use, the movement of the type-carrier, viewed sidewise, at the instant of type-impact being perpendicular to the platen. As seen in Figure 2, the upper types 26 form upper and lower case tiers as do also the lower types 27, the upper-case types being brought into use by shifting the platen 24.

The typewriter-frame 15 is constructed principally on horizontal and vertical lines to give the machine an erect appearance, and the banks of the keyboard 22 have their usual normal positions at the front of the frame 15 as shown in Figure 2. Thus a front wall 25 of the typewriter-frame may be vertical, and the front, and the rear and side portions of said frame may also be vertical, and the base may be horizontal.

In view of the desired erect appearance of the machine, it has been usual heretofore, in machines employing the kind of type-actions seen in said Going patents, to lay out the internal

mechanism within the frame 15 with reference to horizontal and vertical layout coordinates, and to have the printing-line where the platen is intersected by a horizontal plane passing through the platen-axis. It will be seen that the upper and lower types 26 and 27 are spaced vertically, and that the type-carrier array, which is directly forward of the platen, therefore occupies a good deal of room above the horizontal level of the platen-axis.

The type-carriers are moreover guided by a slotted segment 28 which also forms a cover over the rear portion of the type-carrier array (said array being represented by said segment 28), said cover taking up still more room above the platen-axis level. Thus, with the heretofore adopted horizontal and vertical coordinates of reference used in laying out the internal mechanism, said segment 28, which was the highest part obstructing the view of the printing-line, occupied the position indicated by the dotted outline 28^a, Figure 2, and visibility of the printing-line on the platen 24 was therefore possible only at the steep and inconvenient angle indicated by the slope of the dotted line 29 which represents the line of sight to a printing-line position 34.

According to the present invention, the type-actions 16 and the type-carriers 20 are laid out with reference to inclined coordinates, such as a transverse coordinate 30, inclined, say 10 degrees, from the horizontal, and a coordinate 31 perpendicular thereto. Said inclined coordinates 30 and 31 intersect at the axis 32 of the platen, and the type-actions 16 and type-carriers may therefore be regarded as having been turned about the platen-axis 32 in comparison with the type-actions and type-carriers of said Going patents.

The result of such turning is to lower the printing-line from its former position 34 to a new position 35. There is, however, a much greater lowering of the type-carriers 20 and of the overlying segmental cover 28, so that visibility of the new printing-line is substantially increased as is indicated by the substantially lesser slope of the dotted line 31 which indicates the substantially improved angle of visibility.

As seen in Figure 2, the described turning of the interior mechanism also improves the appearance of the machine, in that it is substantially of less height. This improvement in appearance is particularly striking when there is used a segmental shell or cover 38 over the front of the type-actions. Heretofore said cover 38 occupied the elevated position indicated by the dotted outline 38^a, Figure 2. The described turning of the internal mechanism enables said cover 38 to be substantially lowered as indicated by the full outline of said cover in comparison with the dotted outline 38^a. The top cover 38 may moreover have the inclination of its upper surface as shown in Figures 2 and 5, but this is the only part associated with the framework 15 which is inclined, and since such cover-inclination is from the horizontal, the erect lineaments of said framework are preserved. The inclination of the top cover 38 improves the appearance of the machine in that the slope of the top of said cover has the effect of softening the contour of the machine.

Each type-carrier 20 is guided in its headlong movement toward the platen by links 16^a and 16^b of the type-action, as set forth in said Going patents.

Since the parts forming the type-actions 16 and type-carriers 20 are laid out with reference

to the inclined coordinates 30, 31, the other parts of the mechanism within the frame 15, such as parts for supporting a platen-carriage 40, the parts forming a carriage-escapement mechanism 41, and certain other devices may also be laid out with reference to said inclined coordinates, or, in other words, may be also turned about the platen-axis 32. This preserves the relative interference-avoiding dispositions of these parts, as established in existing machines built according to said Going patents. It is therefore possible to use, in the present improved machine, parts that are substantially of the same design as were used in said existing machines; and the benefit 15 of substantially improved visibility of the printing-line and of improved appearance of the machine is afforded by reason of the same parts-design, at little expense. Moreover, there is also preserved the ease of machine operation and excellent quality of type impressions characteristic 20 of said existing machines.

Referring now to said other parts, as are also laid out from the inclined coordinates 30, 31, there is a cross-bar or platform 43 fastened by 25 screws 44 to side-members 45 of the machine-frame 15. Upon said platform 43 rests a bolster 47, which supports the platen-carriage 40 by means of a rock-shaft 48, journaled in lugs 49 of said bolster. Arms 50 of said rock-shaft 48 30 enable the latter, when operated by a case-shift key-train, not shown herein but described in Patent No. 1,661,799, dated March 6, 1928, to Going, to raise and lower a track-bar 51 along which the platen-carriage 40 runs.

35 The bolster 47 extends from side to side of the machine-frame 15, see Figure 3, and, by reason of the inclination of the platform 43, said bolster is guided for fore-and-aft adjustment of the platen in a direction paralleling the transverse 40 layout coordinate 30. Fore-and-aft adjusting movement of the bolster is effected by improved means, which will be described later, and which are manipulatable for the usual purpose of bringing the platen forward or rearward, in accordance 45 with the number of superposed work-sheets positioned around the platen, it being understood that the type-carriers 20 have the limited printing-movement which is characteristic of printing quietly by pressure.

50 Only the middle portion of the bolster 47 rests directly upon the platform 43, as at 52, the end bolster-portions being above raised seats 53 at the ends of the platform 43, and bearing against said seats by means of screw-studs 54, adjustable 55 in the bolster for the purpose of properly seating the bolster on said platform 43. To retain the bolster 47 against upward displacement, said bolster has a forwardly-projecting ledge 56 slidably abutting an overlying segment 57, which also supports the type-action brackets 17, as at 58. 60 Figure 2. The segment 57 has arms 60, Figures 2 and 3, whereby said segment is secured to the platform 43 by screws 61. The bolster-ledge 56 is of such length as to slidably fit between the segment-arms 60, the bolster being thereby retained at its front portion against lateral displacement. The bolster extends substantially toward the rear of the machine, to support other mechanism, as will presently appear, and consequently overhangs rearwardly the platform 43. 65 Improved means for supporting the rear bolster-portion overhanging the platform 43 will be described later.

70 The relative arrangement of the platform 43, the bolster 47, the segment 57 and the carriage

40 may be substantially as set forth in said Going patents, it being understood, however, that, according to the present improvements, these parts are laid out with reference to the inclined coordinates 30 and 31.

5 There is mounted on the carriage 40 a letter-feeding rack 63 meshing with a pinion 64, fastened to one end of a shaft 65, which end is journaled in the track-bar 51, as indicated in Figure 2. Said shaft 65 extends downwardly to present, for cooperation with a dog-rocker 66, an escapement-wheel 67, splined to the lower end of the shaft 65 and retained against axial displacement by a bracket 68 secured to the bolster 47. The splining of the escapement-wheel 67 to the shaft 65 and the retention of said wheel against axial displacement, permit the shaft 65 to move endwise, in accordance with the case-shifting movements of the carriage 40. The dog-rocker 66 formed as seen in Figure 6 may be pivoted between ears 69, Figure 2, of the bracket 68. The dog-rocker 66 has a spring-pressed pivoted holding dog 70 normally in engagement with the escapement-wheel 67, and retractable therefrom to release the carriage for tabulating. The dog-rocker 66 has also a spring-pressed pivoted stepping dog 71. The described escapement-devices are, in respect to the design of the individual parts and the relative dispositions of said parts, substantially along the lines set forth in said Going Patent 1,682,330, it being understood, however, that, for the purpose of the invention, the parts are laid out with reference to the inclined layout coordinates 30, 31, and may therefore be regarded as having been turned about the platen-axis in conformity with the turning of the platform 43 and bolster 47.

35 Each key 21 of the keyboard 22 is mounted upon a key-lever 73 whose portion 74 forwardly of the dotted reference-line 15, Figure 2, may be similar to that used in prior machines, to the end that said keyboard 22 shall have the same arrangement and position in the present improved machine as in said prior machines. The usual ribbon-vibrating means includes the usual universal bar (not shown) that is operated by the usual shoulders or lugs on the bottom edges of the key-levers 76, Figure 2.

40 In accordance with the described inclining of substantially the entire internal mechanism within the machine-frame 15, rear portions 76 of the key-levers are laid out with reference to the inclined coordinates 30, 31; to the end that said rear portions shall bear the same relation to other parts of the inclined internal mechanism as they did in prior machines in which said mechanism was not inclined or turned about the axis 32. A key-lever fulcrum-rod 77 is mounted in a slotted key-lever spacing-bar 78 fastened to the platform 43; and said rod 77 may be regarded, in comparison with prior machines, as having been swung about the platen-axis 32. Points 79 of attachment of the key-levers 73 to the type-action 45 50 55 60 65 70 75 80 85 90 95 100 105 110 115 120 125 130 135 140 145 150 155 160 165 170 175 180 185 190 195 200 205 210 215 220 225 The carriage 40 is driven in letter-feeding steps by a spring-motor 86, which is also operative to drive a ribbon-feeding shaft 87, journaled in a bearing mounted on the platform 43. Said shaft 87 drives a cross-shaft 88 alternatively connectible by the usual ribbon-reversing means, not shown, to vertical shafts 89, which mount ribbon-spools 90 in the same positions as in existing machines, as shown for example in the Remington 10 ton No. 6 noiseless machine as depicted in Going Patent No. 1,665,736, of April 10, 1928.

From the middle portion of the top of the bolster 41, there extends rearwardly and upwardly a transverse wall 91 joined to rearwardly-turned side-walls 92 to form a channel 93. The upper part of the transverse wall 91 has a recess 94 to admit a forwardly-reaching tongue, which forms a counter-stop 95, co-operative with margin-stops 96 of the carriage 40. Said tongue or stop 95 is bent forwardly from an arm 97, which is seen edgewise, and is only shown in such part in Figure 2 as to indicate its improved form. The operation of said arm 97 for margin-releasing and key-locking may be effected by means of parts, not shown, but which may be along the lines used in prior machines and described in Patent 1,255,571, to Anderson, dated February 5, 1918. It will be obvious that these margin-releasing and key-locking parts may also be laid out with reference to the inclined coordinates 30, 31, and to this end Figure 2 shows the stop 95, its arm 97 and the co-operating portions of the margin-stops 96 laid out from said inclined coordinates.

In order to clear a tabulating-stop rack 98, which is newly disposed on the carriage 40 for the purpose of cooperating with novel tabulating mechanism housed in part within said channel 93, the transverse wall 91 and related side-walls 92, forming said channel, rise in front of said rack 98, and are then offset rearwardly above the rack, as seen in Figure 2, to reach the counter-stop 95. The counterstop-arm 97 is therefore bent, as shown, to hug the wall 91 to also pass in front of the stop-rack 98. The stop-rack 98 is supported between side-plates 99 of the carriage 40, and mounts a series of key-settable tabulating stops 100 which may be arranged on said rack as set forth in my Patent 1,901,162, dated March 14, 1933. The side-walls 92 extend under the stop-rack 98 and have flanges 101 to which is attached, by screws 102, a column-like housing 103 which supports parts of said novel tabulating mechanism to be described later.

It will be seen now that the bolster 41 and some of the parts supported overhang the bolster-supporting platform 43 rearwardly to a substantial extent. In addition, therefore, to supporting and slidably guiding the bolster 41 at its forward portion by means of the platform 43, the segment 57, the segment-arms 60, and the bolster-studs 54 bearing on the platform-seats 53, the platform-overhanging portion of the bolster is also supported vertically and laterally and slidably guided by novel means organized as an improvement over bolster-guiding means employed in previous machines and which novel means will now be described.

Joined to the rear portions of the machine-frame side-members 45 is a cross-plate 105 clearing the tabulator-mechanism housing 103 as at 106, Figure 2, but rising at the sides of said housing to present lugs 107 extended forwardly, and inwardly toward one another, to underlie edges 108, Figure 1, of the side-walls 92 which form the channel 93 of the bolster. Said lugs 107 have

adjustable studs 109 against which the edges 108 slidably abut, said edges extending in the direction in which the bolster 41 is adjusted fore and aft. The adjustment of the studs 109 compensates for variations in the height of said edges 108 due to manufacturing tolerances. The cross-plate 105 is also extended upwardly to present lugs 111 opposite the outer sides of the side-walls 92. There is secured to each wall 92 a plate or keeper 112 which, by reason of elongate screw-holes 113 therein, is adjustable in the direction in which the studs 109 are adjusted, keeper-fastening screws 114 passing through said elongate holes 113. Each keeper 112 has a slot 115 whose edges extend parallel to the side-wall edges 108 and slidably fit the inner end 116 of a screw-stud 117 threaded crosswise of the lug 111 as seen in Figure 3. The keepers 112 and crosswise extending screw-studs 117 thus cooperate with the edges 108 and studs 109 to retain the rear portion of the bolster against vertical displacement, and said screw-studs 117 also retain the rear portion of the bolster against lateral displacement, the screw-studs being micrometrically adjustable endwise to abut the side-walls 92 to take up all lateral play at the rear of the bolster 41. For such endwise abutment with said bolster-side walls 92, the screw-studs 117 may have flanges 119 which bear against the outer sides of the plates 112. Set-screws 120 hold the screw-studs 117 in adjusted positions and lock-nuts 121 maintain the adjustment of the studs 109. It will be seen now that the parts for slidably supporting the platform-overhanging portion of the bolster are of simple and inexpensive character and may nevertheless be easily manipulated and afford micrometric adjustments in all necessary directions in order to free the front portion of the bolster from liability of binding in the guiding means afforded by the platform 43 and related guiding parts for the front of the bolster.

In adjusting the described means whereby the platform-overhanging portion of the bolster is slidably guided, the procedure is preferably as follows: With the screws 114 loosened for both keepers 112, the screw-studs 109 are raised or lowered by turning them micrometrically until the bolster moves without binding in the guides afforded by the platform 43 and related parts. The lock-nuts 121 are then tightened. The screw-studs 117 are then moved in or out to micrometrically take up all lateral play at the rear portion of the bolster 41, it being understood that for this purpose the screw-stud flanges 119 bear against the keepers or plates 112. The latter are then tightened in such position by their screws 114 that the lower edges of their slots 115 slidably abut the peripheries of inner ends 116 of the screw-studs 117, thereby retaining the rear end of the platform-overhanging portion 60 of the bolster against upward displacement. The screw-studs 117 are then locked by the set-screws 120. It will be understood that, after these adjustments have been made, the screw-studs 109 remain in abutment with the bolster-edges 108, and are not backed off from the latter, since it is not desired that the upper edges of the keeper-slots 115 be depended on to support the bolster.

Referring now to the improved means for shifting the bolster 41 for platen-position adjustment, a cam-shaft 123 extends from the middle of the machine toward and through the machine-frame side-member 45 to present at the side of the latter a handle or crank 124 for manually

rotating said cam-shaft. At the middle of the machine the cam-shaft 123 has fastened thereto or formed integrally therewith a cam 125. It is desired that means for journaling the cam-shaft 5 123 at its crank-end and retaining it endwise, and means for releasably detenting the cam-shaft in different angular positions be combined in a unitary assembly easily placeable in or removable from the machine, in order to reduce manufacturing and servicing costs; and to these ends the 10 following construction may be employed.

Fastened to the top of the side-members 45 by screws 129, and forming part of the frame 15, are plates 130 extending inwardly toward one another, and rigidly joined to a yoke 131 to form a bridge, which supports a type-guide 132, Figure 2. It may be noted that the inclined type-action-supporting segment 18 may also be rigidly joined at its ends to the plates 130, as indicated 15 at 128, Figure 2. At the middle portion of the yoke 131 of the bridge, there is a pair of lugs 133, 134, for journaling the cam-shaft 123 at points contiguous to the cam 125. The lug 133 gives a 20 full bearing for an inner end 135 of the cam-shaft, but, as indicated in Figures 2 and 3, the other lug, 134, bears only part way around the back of the cam-shaft in order to permit the cam-shaft 123 to be withdrawn or entered endwise without interference between the cam 125 and lug 134, the bolster 47 being movable forward a 25 little to enable the cam 125 to pass the lug 134. A block 126, embodying said lugs 133, 134, is fastened to the yoke 131 by screws 127.

At the crank-end of the cam-shaft, the latter 30 is journaled in a hub 136 of a plate 137, fastened to the outer side of the side-member 45 by screws 139. The crank 124 is fastened to the cam-shaft 123, and carries at its end a knob 140 spring pressed and mounted as shown in 35 Figure 3, said knob having a stem 141, which may be entered in or withdrawn from any one of a series of holes 142 located in the plate 137 to determine and maintain different angular positions of the cam-shaft 123. The latter is maintained against endwise displacement, when the parts are positioned in the machine, by abutment of the crank 124 with the outer end of the hub 136, and by abutment of a shaft-collar 143 with the inner end of the hub. The plate 137 40 may have stops 144 to limit the swing of the crank 124 in opposite directions.

It will be seen now that the described parts at the crank-end of the cam-shaft are together with the cam-shaft 123 and its cam 125, assembled as a unit which is easily placed in the machine and easily removed therefrom.

The bolster 47 has an abutment bearing on the cam 125, said abutment being preferably in the form of a screw 146 threaded in a plate 147 50 fastened to the bolster 47 by screws 148. The end of the abutment-screw 146, and therefore the bolster 47, follows the cam 125, inasmuch as said bolster is pressed rearwardly, toward the cam 125, by suitable springs such as leaf-springs 149 55 fastened at one end to the key-lever bar 78 by screws 151, the other ends of the springs 149 pressing upon studs 152 of the bolster which also prevent the leaf-springs from turning.

For single work-sheet typing, the cam-shaft 70 123 is in such angular position, as seen in Figure 2, that the highest point of the cam 125 is opposite the abutment-screw 146. In correspondence with said primary angular position of the cam-shaft, said abutment-screw 146 will have 75 been initially adjusted to bring the printing-face

of the platen 24 to such position that the types 26, 27 make proper impression upon the single work-sheet. With the cam-shaft 123 thus set for normal or single-sheet printing-position, the stem 141 of the crank 124 will be in the first hole 142 of the detent-plate 137.

It will be seen now that as the cam-shaft crank 124 is rotated from the first hole 142 to other hole-positions, the cam 125 will be rotated clockwise of Figure 2, thereby causing the bolster 47 and hence the platen 24 to be shifted rearwardly under the influence of the bolster-springs 149, the extent of the rearward shift depending on the contour of the cam 125, and its angular position as determined by means of the detent-holes 142. It will also be seen that as the cam-shaft 123 is rotated counterclockwise from any hole 142 other than the first hole 142, the cam 125 will force the bolster forwardly against the pressure of the springs 149, thereby also bringing the platen forwardly.

The tabulating mechanism includes a row of denominational keys 160 on upright stems 161 at the front ends of key-levers 162, operable to selectively bring upstanding denominational stop-blades 163 into co-operation with the rear ends of the key-set stops 100 of the carriage. The key-levers 162 converge rearwardly, so that their rear ends 164 underlie the lower ends 165 of said blades 163, said rear lever-ends 164 and lower blade-ends 165 being kept in alignment by being guided in slots 166 of the aforesaid housing 103, in which said blades 163 are mounted. The key-levers 162 swing about a fulcrum-rod 168 mounted on arms 168 of the framework.

In order that the lifting of any denominational blade may be translated into forward displacement of its upper front edge 167 into the path of a key-set stop 100, and in order that the blade-portions forming said edges 167 may be firmly supported at the carriage-impact, and, further, in order that the carriage-arresting portions of the blades may have the comparatively close letter or denominational spacing, the following construction may be provided.

Near its lower end each blade has a slot 169 whose sides slidably fit a transverse rod 170 fixed in the housing 103. By having the slots 169 inclined, as shown, the lifting of any blade 163 forces its lower end forwardly in consonance with the desired forward displacement of the carriage-arresting edge 167 at the top of the blade which is guided as follows.

The housing 103 has a cap-plate 171 having slots 172 denominationally spaced. The seats of said cap-plate slots 172 and top edges 173 of the blades are preferably straight and are inclined as shown, so that when a blade is lifted, it is also forced forwardly by the seat of its cap-plate slot 172, to bring its carriage-arresting edge 167 into the path of the carriage-stop 100. Spaced from the top-plate 171 is an additional blade-guide 174 fastened to the housing 103 by screws 175 and having slots 176, the bottoms of which co-operate with edges 177 of the blades to keep the top edges 173 within the cap-plate slots 172, when the blades 163 are dropped upon release of the key-levers 162. The cap-plate 171 and the additional guide 174 are relatively disposed as shown, and are respectively above and below the carriage-stops 100, whereby the sides 70 of the slots 172 and 176 are best enabled to support the blades against the carriage-impact during tabulating. Said carriage-arresting-blade edges 167 may extend parallel to the inclined coordinate 31, in order to be operative in the 75

upper-case as well as in the lower-case position of the carriage 40.

In addition to, and similar to, the denominational blades 163, there is an upstanding blade 5 178, also having at its lower end an inclined slot 169 and guided at its upper end by an additional slot 172 in the cap-plate 171 and by an additional slot 176 in the lower guide 174. Said additional blade is operative by a key-lever 179 similar to the 10 tabulating-key levers 162 and having a key 180, said additional blade 178 and key-lever 179 being operative to restore any of the key-set tabulating stops 100 on the carriage when the stop to be restored has been tabulated to the denominational 15 blade of lowest denomination, the additional blades 178 therefore adjoining said lowest denominational blade 163, as indicated in Figure 6.

A novel train for setting the carriage-stops 100 individually includes a key-lever 181, similar to 20 the tabulating-key levers 162. Operation of said stop-setting key-lever 181 lifts a blade 182 guided at its lower end in the housing 103 and by the rod 170 similarly to the other blades 163, 178. Instead of reaching upwardly to the same extent as said 25 other blades, the blade 182 has a forwardly-extending arm 183 articulated by means of a pin 184 to the end of an arm 185 forming part of a yoke 186 which may be formed as indicated in Figure 6, and is rotatable upon a cross-shaft 187, journaled in the blade-housing 103. Said yoke 186 also has an arm 188 which presents a finger 189 opposite the stop-restoring edge of the blade 178, said restoring edge being at the rear side of the 30 stops 100, and the stop-setting finger 189 being at the front of said stops 100 as shown in Figure 8. It will be seen now that operation of the key-lever 181 swings the finger 189 to set any stop 100 that, by positioning the carriage, has been brought opposite said finger.

40 Besides being rotatable upon the shaft 187, the yoke 186 is also movable lengthwise of said shaft for the purpose of avoiding jamming of its finger 189 should the carriage be released when said finger, while engaged in setting one of the stops 45 100 rearwardly, is still between two adjacent ones of said stops 100. For this purpose, the yoke 186 is yieldably held, by a spring 190, in its normal position against the side of the housing 103. The pin 184 is freely articulated to the stop-setting-blade arm 183 of yoke 186, in order to permit the described endwise movement of said yoke. An important object attained by the described means for stop-setting is to cause the finger 189, while 50 setting a stop 100, to move squarely toward the latter, so as to avoid the liability of striking adjacent stops, and at the same time to provide for the described jam-avoiding lateral movement of said finger.

60 The shaft 187 has fastened thereto a universal bar 191 operable by any one of the denominational blades 163, for the purpose of releasing the carriage from the escapement-wheel 67. The universal bar 191 has an arm 192, which, in effect, 65 forms an arm of said shaft 187. Each denominational blade 163 has a forwardly-reaching finger 193 to engage the universal bar 191. The carriage-releasing arm 192 of the universal bar 191 is connected by a link 194 which ranges downwardly and forwardly for articulation with a slot 195 of a dog-releasing lever 196, pivoted to the bracket 65 70 68 which mounts the dog-rocker 66. At its lower end portion, the link 194 is guided in proper direction by passing between the rod 170 and another rod 198 which supports an anchor-piece 199, to

which are attached springs 200 which serve to restore the blades 163, 178 and 182. The upper end of the stop-setting blade 182 may be retained against lateral displacement by playing in a slot 201 afforded by the universal bar 191. A spring 5 197 applied to the dog-releasing lever 196 urges the latter and the rest of the universal-bar train to normal, Figure 2 position.

The stop-restoring blade may also have a cam 10 203 which is operative to restore all the set stops 100 by a run of the carriage when said stop-restoring blade 178 is maintained in forwardly-projected position by its key-lever 179.

15 Figure 7 is a diagram representing modification of the tabulating mechanism when the latter is to be used only for column-tabulating. In this case only one stop-plate, 163a, is employed, and this one blade is in the position occupied by the lowest denomination-blade of the denominational set, in order to be properly co-operative with the stop-restoring blade 178, it being understood that, when a stop 100 is to be restored, the carriage is tabulated to said column-stop blade 163a. The column-tabulating key may be in the form of a 20 bar 204, disposed as shown at Figure 7, between the stop-clearing and stop-setting keys 180, 202. Said tabulating-key bar 204 may be mounted upon key-levers 205 which may be yoked together, as indicated in Figure 7, by a fulcrum-sleeve 206, 25 a rivet 207 and a rod 208.

30 The typing key-levers 73 normally abut a cushion-stop 209 mounted on a comb-plate 210 formed and mounted as shown in Figure 2 to guide the stems 161 of the tabulating key-levers. Said stems 161 may have stroke-limiting ears 211 striking a cushion-stop 212. Normally the tabulating key-levers rest against another cushion-stop 213, the stops 212, 213 being mounted on a plate 214 secured with a comb-plate 215 for the typing key-levers 73 to a cross-bar 216. The typing key-levers 35 73 are retracted by springs 218, anchored to a plate 219 having links 220 held at their forward ends in the bar 216 and adjustable endwise relatively to said bar 216 as indicated in Figure 2, for the purpose of adjusting the springs 218.

40 The portion of the shell or top cover 38 which immediately overlies the type-carriers 20 is segmental in form and is declined from the horizontal as shown, said declined portion having laterally-extending horizontal plates or flanges 222 which rest upon the frame-side members 45, as at 223, and are even with the aforementioned plates 130, the latter being overlapped by the segmental portion of the cover 38, as indicated 45 50 at 224. Suitable screws, such as 226, secure the shell 38 to the frame-side members 45. The slotted segment 28 which guides the type-carriers 20 rests on inclined abutments 227 rising from the plates 130 and is secured by screws 228.

55 The side-plates 99 of the carriage 40 and the usual mechanism, such as line-spacing and other devices (not shown) contiguous to said side-plates, may be covered by casing-plates 229, which, as indicated in Figure 2, may be shaped to give the carriage 40 an appearance consonant with the described other features of improved machine-appearance. 230 represents the usual rail of the carriage which bears against the part of the bolster 41 formed by the walls 91, 92, to support the carriage as the types 26 or 27 print by pressure against the platen 40.

60 It will be seen that according to the invention, substantially the entire internal mechanism, which comprises all the parts of the typing instru- 65 70 75

mentalities relatively located as in machines built according to said Going patents, is turned about the platen-axis to gain substantial benefits, viz., (1) to improve the visibility of the printing-line, 5 and (2) to improve the appearance of the machine, it being evident that by lowering the top cover 38 which forms part of the machine-frame 15 as shown in Figure 2, there is eliminated the somewhat ponderous appearance which the machine had when the cover 38 was in the old position 38^a. These important benefits increase the salability of the machine and the customer's satisfaction therewith.

The improvements in the means for adjusting the platen 24, and for tabulating the carriage, 15 also afford important benefits, it being noted that said platen-adjusting means and tabulating mechanism are simple in character, and nevertheless efficient in operation. It will be noted that 20 with the exception of the tabulating-key levers 162 and the carriage-stops 100, the improved tabulating mechanism, including the stop-setting and stop-clearing devices, and the described liftable, and at the same time forwardly movable, 25 blades, may be assembled as a unit, all mounted in the housing 103, and easily placeable upon, or removable from, the machine.

Variations may be resorted to within the scope of the invention, and portions of the improvements 30 may be used without others.

Having thus described my invention, I claim:

1. A front-strike typewriter including a revoluble platen, a machine-frame constructed substantially on horizontal and vertical lines to give 35 said frame an erect appearance, type-carriers radially arrayed directly forward of the platen for headlong throw toward the platen, each type-carrier having a plurality of vertically-spaced types, the type-carrier array reaching up to a 40 level higher than the printing-line, a keyboard at the front of said frame from which key-levers extend rearwardly, and type-actions connecting the rear portions of the key-levers, within said frame, to said type-carriers, said rear key-lever 45 portions, type-actions and type-carriers forming an internal unitary mechanism which is laid out with reference to inclined coordinates, perpendicular to each other, the use of said inclined layout-coordinates having the effect as of said 50 internal unitary mechanism having been depressed as a unit about the platen-axis, whereby the type-carriers are depressed to occupy substantially less room above the horizontal level of the platen-axis to improve the visibility of the 55 printing-line, said turning of the internal mechanism being effected without changing the erect lines of said machine-frame or the normal position of said keyboard relative to said frame.

2. A front-strike typewriter including a revoluble platen, a machine-frame constructed substantially on horizontal and vertical lines to give 60 the frame an erect appearance, type-carriers radially arrayed directly forward of the platen for headlong throw in convergent vertical planes 65 toward the platen, a segment overlying and slidably guiding the type-carriers at their rear portions, the type-carrier array and said segment reaching up to a level higher than the printing-line, a keyboard at the front of said frame from 70 which key-levers extend rearwardly, and means connecting the rear portions of the key-levers within said frame to said type-carriers, said rear key-lever portions, type-actions and type-carriers forming an internal mechanism which is laid out 75 with reference to inclined coordinates substan-

tially as set forth, said segment being part of said machine-frame and being also laid out with reference to said inclined coordinates, so that the visibility of the printing-line is substantial, the erect lines of said machine-frame and the position of said key-board relative to said frame being preserved, said segment being the only part of said machine-frame depressed, and its inclination, being from the horizontal, having the effect of softening the contour of the machine.

3. A front-strike typewriter including a revoluble platen, a machine-frame, type-carriers radiating directly forward from the printing-point for headlong throw toward the platen, type-actions for said type-carriers within said frame and reaching to a level higher than a plane passing through the printing-line and the platen-axis, means forming a cover above said type-carriers and type-actions, said cover-means being part of said frame, said type-carriers, type-actions and cover-means being pitched downwardly and thereby depressed about the platen-axis to lower them and the printing-line, said machine-frame being constructed mainly on horizontal and vertical lines to give it an erect appearance, said cover-means being the only part of said frame which is pitched downwardly, and a keyboard at the front of said frame from which key-levers for said type-actions extend rearwardly, said key-levers arranged so that said keyboard is not pitched downwardly from its normal position.

4. A front-strike typewriter including a revoluble platen, a system of type-carriers and underlying type-actions, said type-carriers extending fore and aft in a radial array directly 35 forward of the platen for headlong throw toward the latter, and a machine-frame including means forming a type-carrier guide and cover, said means overlying said type-carriers and type-actions, said type-carriers and guide and cover-means reaching to a level higher than the level of the printing-line, a keyboard at the front of said frame from which key-levers extend rearwardly to the type-actions, the movement of the type-carriers, viewed sidewise, at the instant of 40 type-impact being substantially perpendicular to the platen, said type-carriers and type-actions being laid out to print at a line below the horizontal level of the platen-axis, said type-carriers, said overlying guiding and cover means and said 45 type-actions forming a unit which is depressed about the platen-axis, to render the printing-line visible, said frame being otherwise laid out on horizontal and vertical lines to give the machine an erect appearance, the keyboard having the 50 normal usual position.

5. A front-strike typewriter including a main frame, a case-shiftable platen, and a system of type-actions including type-carriers, the type-carriers radiating directly forward from the 60 platen and partly above the printing-line for headlong dip rearwardly to the platen, said main frame including a segmentally-formed portion overlying said type-carriers and forming therefor a radial guide and a shell-like cover, each 65 type-carrier having a plurality of pairs of upper and lower case types vertically spaced, said type-actions and the overlying segmental portion being laid out with reference to inclined coordinates perpendicular to one another, said type-carriers and segmental frame-portion being accordingly depressed at the front, to render the printing-line visible, said depressed segmental frame portion having laterally-extending horizontal plates secured to the side members of said 70 75

frame, the rest of said frame being constructed substantially on horizontal and vertical lines to preserve the erect appearance of the machine.

6. A front-strike typewriter including a main frame constructed substantially on horizontal and vertical lines to present an erect appearance, a keyboard at the front of said frame from which key-levers extend rearwardly, a revolute platen, a platen-carriage, platen-carriage-supporting means comprising a fixed platform, a bolster resting on said platform and mounting said carriage, a system of type-actions connected to and rising above the rear portions of said key-levers, a system of type-carriers at the top of said type-actions and radiating directly forward from the printing-point for headlong dipping rearwardly toward the latter, means co-operating with said platform to support and guide said bolster, and carriage-feeding devices mounted on said bolster, said type-carriers reaching to a level higher than the printing-line, said type-actions being disposed immediately in front of said platen-supporting means, said platen, said type-carriers, type-actions, platen supporting and adjusting means, letter-feeding devices, and the rear parts of said key-levers forming an internal unit which is pitched downwardly to depress the type-bars, to render the printing-line visible, said depression of the unit being effected without changing the erect lines of said main frame or the regulation normal position of said keyboard relative to said frame.

7. A front-strike noiseless typewriter including a main frame, a revolute platen, a system of type-actions 16, and type-carriers 20 located partly above the printing-line and disposed directly forward of the platen for headlong dip toward the latter, said main frame including a segment 28 overlying said type-carriers and forming therefor a radial guide, said frame also including a shell-like cover 38, each type-carrier having types 26, 27, said type-carriers 20 and said overlying segment 28 and cover 38 reaching to a level above the platen-axis level, said type-actions 16, type-carriers 20, and the overlying segment 28 and cover 38 being laid out with reference to inclined coordinates 30, 31, whereby said type-carriers 20, segment 28 and cover 38 as a unit are depressed about the platen-axis 32, to substantially improve the visibility of the printing-line, the rest of said frame being constructed substantially on horizontal and vertical lines to preserve the erect appearance of the machine.

8. A front-strike typewriter of the noiseless class having a system of type-bars mounted to print upon the front of a revolute platen, the type-bars moving in convergent vertical planes through a center guide and against the front of the platen to render the line of print completely visible at the completion of the operation of the usual up-and-down ribbon-vibrator, said type-bars forming a substantially horizontal row and reaching to a level higher than the line of typing, said type-bars and said platen forming a unit which is dropped about an axis substantially coincident with the axis of the platen, to such an extent that the type-impressions upon the platen fall on a line which is below the horizontal plane of the axis thereof, with the type-bars below the line of vision from the operative's eye to the typed line on the platen.

9. A front-strike typewriter of the noiseless class having a system of type-bars mounted to print upon the front of a revolute platen, the type-bars moving in convergent vertical planes

through a center guide and against the front of the platen to render the line of print completely visible at the completion of the operation of the usual up-and-down ribbon-vibrator, said type-bars forming a substantially horizontal row and reaching to a level higher than the line of typing, said type-bars having a system of operating trains, and said platen having a carriage; said system of trains, said carriage, said platen and said type-bars all forming a unit which is dropped about substantially the axis of the platen to locate the top line of the type-bars at a position below the line of vision from the eye of the operative to the typed line on the platen just below the level of the axis thereof.

10. A front-strike typewriter of the noiseless class having a system of type-bars mounted to print upon the front of a revolute platen, the type-bars moving in convergent vertical planes through a center guide and against the front of the platen to render the line of print completely visible, said type-bars forming a substantially horizontal row and reaching to a level higher than the line of typing, said type-bars having a system of operating trains, and said platen having a carriage; said system of trains, said carriage, said platen and said type-bars all forming a unit which is dropped about substantially the axis of the platen to locate the top line of the type-bars at a position below the line of vision from the eye of the operative to the typed line on the platen just below the level of the axis thereof, said trains also including key-levers, and said dropped unit also including a carriage-escapement mechanism.

11. A front-strike typewriter of the noiseless class having a system of type-bars mounted to print upon the front of a revolute platen, the type-bars moving in convergent vertical planes through a center guide and against the front of the platen to render the line of print completely visible, said type-bars forming a substantially horizontal row and reaching to a level higher than the line of typing, said type-bars having a system of operating trains, and said platen having a carriage; said system of trains, said carriage, said platen and said type-bars all forming a unit which is dropped about substantially the axis of the platen to locate the top line of the type-bars at a position below the line of vision from the eye of the operative to the typed line on the platen just below the level of the axis thereof, said trains also including key-levers, and said dropped unit also including a carriage-escapement mechanism.

12. A front-strike typewriter of the noiseless class having a system of type-bars mounted to print upon the front of a revolute platen, the type-bars moving in convergent vertical planes through a center guide and against the front of the platen to render the line of print completely visible at the completion of the operation of the usual up-and-down ribbon-vibrator, said type-bars forming a substantially horizontal row and reaching to a level higher than the line of typing, said type-bars having a system of operating trains, and said platen having a carriage whose top portions are level; said system of trains, the under portions of said carriage, said platen and said type-bars all forming a unit which is dropped about substantially the axis of the

platens to locate the top line of the type-bars at a position below the line of vision from the eye of the operative to the typed line on the platen just below the level of the axis thereof, and a 5 cover-plate mounted over said type-bar system and forming part of the dropped unit, so that neither type-bars nor cover-plate obstruct the view of the typed line; the inclined cover-plate being dropped to a position about level with the 10 top of the platen to afford access to the platen and the paper thereon.

13. A front-strike typewriter of the noiseless class having a row of type-bars mounted to move rearwardly to print upon the front of a revolute 15 platen, the platen being in rear of and about level with the type-bars, the type-bars forming a unit which is dropped about an axis in rear of the impression point, whereby the type-impressions upon the platen fall on a line which is just 20 below the horizontal plane of the axis thereof; the type-bars being normally below the line of vision from the operative's eye to the typed line on the platen.

14. A front-strike typewriter of the noiseless 25 class having a row of type-bars mounted to move downwardly and rearwardly to print upon the front of a revolute platen, the platen being in rear of and about level with the type-bars, the type-impressions falling upon the platen on a 30 line which is just below the horizontal plane of the axis thereof; the type-bars being normally below the line of vision from the operative's eye to the typed line on the platen, said type-bars having a system of operating trains, and said 35 platen having a carriage, said system of trains and said carriage and platen and type-bars forming a unit which is dropped substantially about the axis of the platen to bring the type-bars to a position below the line of vision from 40 the eye of the operative to the typed line on the platen.

15. A front-strike typewriter including a revolute platen, an external machine-frame having its body constructed substantially on vertical 45 lines for imparting to said frame an erect appearance, a unitary typing mechanism within said frame and including a system of multiple-type carriers radially arrayed directly in front of the platen for headlong throw back to the 50 platen, the type-carrier array reaching up to a level higher than the printing-line on the platen, said frame being a mount upon which said unitary typing mechanism as a unit is supported in forwardly and downwardly inclined posture, said 55 interior unit swung down about a point that is substantially coincident with the platen-axis, whereby type-carriers occupy a modicum of vertical room above the level of the platen-axis, and hence expose to full view the printing-line, 60 and a keyboard at the front of the frame having normally posed keys operatively connected to the interior inclined typing mechanism.

16. A front-strike typewriter including a revolute platen, an external machine-frame having its body constructed substantially on vertical 65 lines for imparting to said frame an erect appearance, a unitary typing mechanism within said frame and including a system of multiple-type carriers radially arrayed directly in front of the platen for headlong throw back to the 70 platen, the type-carrier array reaching up to a level higher than the printing line on the platen,

said frame being a mount upon which said unitary typing mechanism as a unit is supported in forwardly and downwardly inclined posture, said interior unit swung down about a point that is substantially coincident with the platen-axis, 5 whereby type-carriers occupy a modicum of vertical room above the level of the platen-axis, and hence expose to full view the printing-line, a keyboard at the front of the frame having normally posed keys operatively connected to the 10 interior inclined typing mechanism, and a cover-plate mounted over the type-bar system, said cover-plate being pitched forwardly and downwardly.

17. In a front-strike typewriter including a revolute platen, an external machine-frame having its body constructed substantially on vertical lines for imparting to said frame an erect appearance, and a unitary mechanism within said frame and including a system of multiple-type carriers radially arrayed directly in front of the platen for headlong throw back to the platen, said unit also including a carriage, appurtenances therefor, inclusive of tracks and driving and feeding mechanism, said carriage and its said appurtenant mechanism being adapted and fitted to said type-system, the type-carrier array reaching up to a level higher than the printing-line on the platen, said frame being a mount upon which said typing mechanism, said carriage and said 30 carriage appurtenances, all as a unit, are supported in forwardly and downwardly inclined posture, said interior unit depressed about a point that is substantially coincident with the platen-axis, whereby type-carriers occupy a modicum of vertical room above the level of the platen-axis, and hence expose to full view the printing-line. 35

18. In a front-strike typewriter including a revolute platen, an external machine-frame having its body constructed substantially on vertical 40 lines for imparting to said frame an erect appearance, a unitary mechanism within said frame and including a system of multiple-type carriers radially arrayed directly in front of the platen for headlong throw back to the platen, 45 said unit also including a carriage, appurtenances therefor, inclusive of tracks and driving and feeding mechanism, said carriage and its said appurtenant mechanism being adapted and fitted to said type-system, the type-carrier array reaching up to a level higher than the printing-line on the platen, said frame being a mount upon which said typing mechanism, said carriage and said carriage appurtenances, all as a unit, are supported in forwardly and downwardly inclined 50 posture, said interior unit depressed about a point that is substantially coincident with the platen-axis, whereby type-carriers occupy a modicum of vertical room above the level of the platen-axis, and hence expose to full view the printing-line, 60 and a level keyboard at the front of the frame having normally posed keys operatively connected to the interior inclined typing system, said type-bars being connected to fore-and-aft key-levers, 65 whose rear portions have a forward and downward pitch to correspond with the posture of said unit, and whose front portions extend forwardly in level condition to bear the keys, the rear portion and front portion of each lever forming an 70 oblique elbow.
